UNITED STATES PATENT OFFICE.

LYLE F. GRAY, OF BEAVER DAM, WISCONSIN, ASSIGNOR TO PARAMOUNT HOSIERY FORM DRYING CO., OF CHICAGO, ILLINOIS, A CORPORATION OF ILLINOIS.

HOSIERY-FINISHING FORM.

1,254,626.

Specification of Letters Patent. Patented Jan. 22, 1918.

Application filed March 19, 1917. Serial No. 155,889.

To all whom it may concern:

Be it known that I, LYLE F. GRAY, a citizen of the United States, residing at Beaver Dam, in the county of Dodge and State of Wisconsin, have invented certain new and useful Improvements in Hosiery-Finishing Forms, of which the following is a specification, reference being had therein to the accompanying drawing.

10 This invention relates to hosiery finishing structures and more particularly has reference to hosiery drying and shaping forms.

The object of the invention is primarily to provide, in such forms, means for effecting the essentially important functions of flattening out and smoothing certain parts of the fabric of hosiery which, for one reason or another, are not brought to proper shape and condition by the knitting machine:

15 As is known in the trade, in the knitting of seamless hosiery (so-called) the pouch or section of the toe-portion of the hosiery-article includes, in part, a gore formed by the machine, a looper's seam

20 made by the looper, and a knot made at the juncture of the bore with the seam. The pouch, in being preliminarily shaped, has a tendency to cup, that is, it rolls up at the edges and has a cup-like formation. It is

25 desirable, in the finishing of the goods, to remove this cup, to stretch and iron out the bore as much as possible, and to shape the toe-portion. Heretofore, this has in part been accomplished by a pressing operation—

30 additional to the regular drying operation—or by manipulating the goods over the surface of the drying-form but, on particularly heavy goods, these are not always readily and adequately performed. It is the aim

35 of my invention, therefore, to provide means for effecting this result and with a degree of certainty and facility that makes for a better finish on the product.

With this object in view, the invention resides in the structure, and in the components thereof, all as more particularly set forth in the following description.

In order that the invention may be readily comprehended, I have disclosed a preferred embodiment thereof in the accompanying drawings; these, however, being illustrative and make clear that the invention is susceptible of a wide range of modification

without departing from or sacrificing the underlying principles and salient features 55 of the invention.

In these drawings:

Figure 1 is a view in elevation of a hosiery drying and shaping form embodying my invention;

Fig. 2 is a fragmentary view in central section thereof; and

Fig. 3 is a fragmentary view in elevation of the same showing a portion of a stocking partly disposed on the form.

Referring to the drawings, the reference character 1 designates a hosiery-drying and shaping form which, in this instance, is hollow to contain a heating medium (such as steam or the like) to heat it from within. 70 This form is preferably provided with relatively reduced edge-portions 2 adapted to produce a crease-like formation in the hosiery-article 3 superposed on the form. This hollow form, in general, is of the general 75 type disclosed in United States Patent No. 1,207,496, granted December 5th, 1916.

The form, being relatively thin in cross-section as shown, presents two sides, the edge-portions being beveled and terminating 80 in the edge-portions 2. Each of the sides includes a primary fabric-flattening surface 4 which extends to said edge-portions and encompasses an expanded portion 5 constituting an auxiliary fabric-flattening surface. Preferably, this auxiliary surface 5 is elongated longitudinally of the foot-portion 6 of the form and presents a ridge 6^a which extends from adjacent the end 7 of the toe-section back for a distance, say, of a couple 90 of inches. The shape and dimensions of the auxiliary surface may be varied to meet the requirements, the desideratum being, however, that it shall occupy a plane different from the primary surface and this is secured, in this instance, by casting the metal thicker at that point. The result is that, while the primary surface is performing its intended function of smoothing and flattening the body-portion of the foot of the 100 hosiery-article and, in coöperation with the edges 2, effecting a pronounced ironing and shaping of the same, the auxiliary surface will at the same time effect a transverse stretching of the fabric and this, in conjunction with the stretching and fixing action

105

2

of the primary surface, tends to shrink and eliminate the normal fullness of the pouch of the foot-portion. In this way, the toe-section of the article is shaped as regards both its edge-portions and its intermediate portion. Moreover, the ridge 6^a tends to iron and flatten out the gore 8 in the article and, likewise, the looper's knot therein. The ridge also serves as a guide for the finger 10 of the operator properly to aline the gore with it and, thus, position both gores of the article exactly opposite each other.

By reason of the fact that the auxiliary surface or portion includes an additional amount of metal and, thereby, presents a greater heat-retaining area, this auxiliary surface directs a greater amount of heat to the fabric adjacent the gore and knot and thereby tends to quicken the heating capacity of the form in that locality where the reinforced fabric, being thicker, etc., might otherwise not be dried with as much facility as the primary surface effects its drying function.

25 The rear portion of the ridge 6^a is preferably formed with a fairly substantial bevel or inclined surface 9 and this is adapted to be engaged by the fabric and tends, when the fabric shrinks and grips the same—as it naturally does in practice—to anchor such fabric against creeping toward the end of the toe-section.

From the foregoing, it will be perceived that I have devised a drying and shaping structure which has the capacity, first, of effecting a shrinking and fixing of the hosiery-fabric within a zone where it ordinarily is normally too full; secondly, of effecting a quick drying of the fabric which is thicker at that point; and, third, of presenting a guiding means to enable the operator more accurately and quickly to position the gored sections of the hosiery-article for proper relative arrangement of its wales, etc.

45 What I claim is:

1. A hosiery drying and shaping form including a foot-portion comprising sides, each consisting of a primary fabric-flattening and smoothing surface extending inwardly from the edges of the portion and an auxiliary gore-smoothing surface disposed approximately centrally of said edges extending longitudinally of the foot-portion 50 and merging into said primary surfaces, a

section of said auxiliary surface outstanding beyond the plane of the primary surface.

2. A hosiery drying and shaping form comprising a foot-portion including a toe-section comprising primary fabric-flattening and smoothing surfaces and intermediate auxiliary gore-smoothing surfaces encompassed by the primary surfaces and extending in the longitudinal direction of the foot-portion, each auxiliary surface having a section outstanding substantially beyond the plane of the primary surface.

3. A hosiery drying and shaping form including a foot-section having oppositely-disposed fabric-ironing sides comprising a primary flattening and smoothing surface and an auxiliary fabric-shrinking surface encompassed by the primary surface and comprising a pyramidal portion and a fabric-anchoring portion.

4. A hosiery drying and shaping form including a foot-section having oppositely-disposed fabric-ironing sides comprising a primary flattening and smoothing surface extending in one direction into a toe-portion 80 and an auxiliary fabric-shrinking surface encompassed by the primary surface and comprising a pyramidal portion and a fabric-anchoring portion extending in a direction away from the toe-portion.

5. A hosiery drying and shaping form including a foot-section having oppositely-disposed fabric-ironing sides comprising a primary flattening and smoothing surface terminating in one direction in crease-producing edges and an auxiliary fabric-shrinking surface encompassed by the primary surface and comprising a longitudinally extending pyramidal portion and a beveled fabric-anchoring portion.

6. A hosiery drying and shaping form including a foot-section having oppositely-disposed fabric-ironing sides comprising a primary flattening and smoothing surface and an auxiliary fabric-shrinking surface encompassed by the primary surface and comprising a pyramidal portion and a fabric-anchoring portion and a ridge-portion.

In testimony whereof I affix my signature in presence of two witnesses.
